ATTORNEY

UNITED STATES PATENT OFFICE.

GEORGE BERNHART, OF AMANA, IOWA.

CARDING-MACHINE.

SPECIFICATION forming part of Letters Patent No. 253,260, dated February 7, 1882.

Application filed April 14, 1881. (No model.)

To all whom it may concern:

Be it known that I, GEORGE BERNHART, of Amana, in the county of Iowa and State of Iowa, have invented certain new and useful 5 Improvements in Carding-Machines; and I do hereby declare the following to be a full, clear, and exact description of the invention, such as will enable others skilled in the art to which it pertains to make and use it, reference being had 10 to the accompanying drawings, which form part of this specification.

My invention relates to an improvement in carding-machines, the object of the same being to provide means for taking the end or waste 15 rovings from the rub-rolls of the finisher-card up over the same and delivering them continuously to the second breaker-card, where they are mixed with the new wool. With these ends in view my invention consists in certain details of construction and combinations of parts, 20 as will be more fully explained, and pointed out in the claims.

In the accompanying drawings, Figure 1 represents a vertical section of the finisher and 25 second breaker-card and their adjunctive parts with my improvement attached thereto. Fig. 2 is a view of the shaft and rolls that drive the conveyer. Fig. 3 is a view of the fifth worker of the second breaker-card. Fig. 4 is an end 30 view of one of the hangers, d^3 , and Fig. 5 is a view of the shaft supporting the rear end of the conveyer-belts.

A represents the main cylinder of the finishing-card, which, together with the second 35 breaker-card, is furnished with the usual feed-rolls, A' , one licker-in, A^2 , one tumbler, A^3 , four workers, A^4 , and four strippers, A^5 , one fancy, A^6 , while the finisher-card A is provided with two ring-doffers, B B, and a rub with two sets 40 of rub-rolls, C C, and the second breaker with only one doffer, J.

D is a shaft journaled in the bearings D' , mounted on arches, which support the rub-rolls of finisher-card, said shaft having two 45 grooved-faced rollers, $a a'$, secured thereto near each end, around which the endless conveyers pass. This shaft is also provided with a pulley, b, on one end thereof, around which a driving-belt, c, passes, the latter extending down 50 and around the driving-pulley E, the latter being secured to a shaft having a cog-wheel thereon, which meshes with a corresponding

cog-wheel on one of the rub-rolls, and has its motion imparted thereto.

The conveyers F are endless belts provided 55 with card-clothing on one face, and receive their motion by the groove-faced rollers $a a'$, above referred to, which are in turn driven by belt c. This conveyer is supported above the finisher-card and second breaker-card by suitable groove-faced rollers, $d d'$, journaled in wooden hangers d^3 , attached to the ceiling. These hangers d^3 are made of wood, and are provided with extra slots, into which the rollers are inserted when the conveyer-belts become loose. These hangers have been found to answer the best purpose, because they require no lubrication, and flying wool does not affect them. The conveyers F, after passing upward from the finisher-card, run in a horizontal direction for some distance, and are then deflected downward, so as to deposit the fillets 60 of waste or end rovings onto the last stripper of second breaker, or the one nearest the fancy. This stripper, which is a part of the second 65 breaker, strips its worker, together with the conveyer-belts, in the same manner that every stripper strips its worker. The rear extremities of the conveyers immediately over the second breaker-card are supported on smooth-faced rollers G, said rollers being journaled on shaft H, which in turn has its bearing in adjustable standards L, secured to the arches of the second breaker-card. This shaft H is 70 revolved by the endless conveyers, and is provided with a cam, g, at one side thereof, adapted to work in the bracket l, secured to the adjustable standard L, the said bracket being provided with a grooved face in which the cam g works, and by which a lateral motion is 75 imparted thereto which distributes the fibers of the waste rovings evenly. These standards L are provided with slots, by which they are pivotally secured to the arches of the second breaker, and adjusted so that the teeth of the 80 conveyer-belts come close to the stripper, and enable the stripper to take the wool quite clean 85 from off the conveyer-belts.

I is the last stripper, or the one nearest the fancy, situated below the ends of the conveyers, and adapted to take the end rovings therefrom and deliver them to the second breaker-card at about the same speed they are delivered from the finisher-card, where they are 90 95 100

worker situated below said stripper, said worker having a girdle of card-clothing removed from each end, which allows the rovings to pass uninterrupted to the doffer, where it is mixed with the new wool, substantially as set forth.

5. In a waste-roving conveyer for carding machines, the combination, with a finisher-card and second breaker-card, of an endless conveyer or conveyers provided with card-clothing on one face and supported above the said finisher and second breaker cards, adjustable hangers, rub-roll gearing of the finisher-card, and suitable mechanism by which the desired motion is imparted to said conveyer, substantially as set forth.

10. In a waste-roving conveyer for carding machines, the combination, with a finisher and second breaker card, the endless conveyer, removable end shafts therefor, and intermediate

removable shafts adapted to be vertically adjusted, as described, of hooks adapted to receive said removable end shafts and hold them up out of the way while grinding and cleaning the cards, and suitable supporting means for said hooks, substantially as set forth.

15. The combination, with the main cylinder of the second breaker-card, of the fifth worker provided with card-clothing of less width than that on the main cylinder, and arranged to form an annular naked space around each end of the fifth worker, substantially as set forth.

In testimony that I claim the foregoing I have hereunto set my hand this 29th day of March, 1881.

GEORGE BERNHART.

In presence of—

CHAS. MOORSHEL,
LEONHARD GRAF.
